Joseph Wadleigh.

JOSEPH WADLEIGH, OF CHEBANSE, ILLINOIS.

Letters Patent No. 85,150, dated December 22, 1868.

IMPROVEMENT IN TONGUES FOR HARVESTERS.

The Schedule referred to in these Letters Patent and making part of the same.

To all whom it may concern:

Be it known that I, JOSEPH WADLEIGH, of Chebanse, in the county of Iroquois, and State of Illinois, have invented a new and useful Improvement in Tongues for Reapers and Mowers; and I do hereby declare and make known that the following is a full, clear, and exact description thereof, reference being had to the accompanying drawings, and the letters and figures marked thereon, which form part of this specification.

My said invention consists in constructing the tongues of reaping and mowing-machines, or other vehicles having a side-draught, with a joint just in front of the point where the double-tree is attached; of such construction that the tongue is rigid and stiff when the machine is being drawn forward, but that will allow the tongue to turn laterally at said joint when the horses are guided to one side to turn the machine in another direction, so as to relieve the necks of the horses from the leverage of the tongue in turning, as is the case with tongues of the ordinary construction, said tongue resuming its original position automatically as soon as the draught comes in a direct line with the stationary part of the tongue or draught-pole, as is hereinafter more fully and explicitly set forth.

To enable those skilled in the art to understand how to construct and use my said improvement, I will proceed to describe the same with particularity, making reference, in so doing, to the aforesaid drawings, in which—

Figure 1 represents a plan or top view of my invention;

Figure 2 represents a similar view when the machine is being turned from its former course;

Figure 3 is a side view of the same;

Figure 4 is a central plan section at the line *x* in fig. 3; and

Figure 5 is a central vertical section at the line *x* in fig. 1.

Similar letters of reference in the several figures denote the same parts of my invention.

A represents the stationary heel of the tongue, which is rigidly attached to the frame of the machine in any suitable manner, and which is constructed with a horizontal recess extending back from its front end a sufficient distance, and entirely across the piece *A*, as indicated clearly in fig. 4, where said recess or slot is marked *a*, its middle part extending farther back than its sides, forming a sloping-faced socket, as indicated in said fig. 4.

The movable part of the tongue, marked *B*, is provided, at its rear end, with a horizontal central tongue or tenon, *b*, which passes back into the aforesaid slot in *A*, its rear end conforming to and fitting into the rear end of the said slot, as indicated.

The object in having a socket at the rear end of the recess *a*, and a corresponding point on the rear end of

the tongue *b*, is to provide for making the draught-pole rigid when backing; and the object of having a longitudinal movement in the pole *B*, is to enable the pole to be moved forward out of said socket, so as to be swung around.

The part marked *A* may be made of wood or iron, and, if desired, may be cast upon and with the frame of the machine.

These two parts are then pivoted together by a pin, *P*, which pin also secures the double-tree *C* in place, and passes through a longitudinal slot, marked *c*, in the tongue *b* of the movable draught-pole, as seen in figs. 4 and 5.

F *F'* represent metallic straps, secured upon the top and bottom of the heel *A*, at the point where the pin *P* passes through, to form bearings for the shoulder on the pin *P* and the nut *m* at its lower end, as shown in figs. 3 and 5, the shoulder on the pin and the lower nut *m* serving to hold the jaws of *A* together, and strengthening them.

The double-tree is held upon the pin *P* and the tongue *A* by means of a nut, *n*, or said pin *P* might be provided with a head for that purpose, if desired. But, by having a nut upon the upper end of said pin, and a shoulder resting on the top of the piece *A* or strap *F*, the double-tree can be removed without withdrawing the pin *P* from the joint in the tongue or pole.

E represents a continuous band, passing around *A*, just at the rear end of the aforesaid recess *a*, to strengthen the same.

D *D'* represent metallic straps, secured upon each of the members of the part *A*, above and below the recess *a*, for the purpose of securing in proper position, upon one or both sides of the tongue, certain supports or lugs *d* *d'*, as shown, through which a pin, *p*, may pass, and in which it may be securely held in place, as desired. Said lugs *d* *d'* are required upon only one side of the tongue, and may be secured in any suitable manner, the side upon which they are to be placed being determined in each machine on the point as to which side of the tongue the side-draught comes, or, in other words, the direction in which the machine is required to be turned when in use. However, lugs may be placed upon both sides, in order that when the machine is being moved from place to place, not being in use, pins may be put in on both sides, to render the pole *B* rigid, and enable the machine to be turned in either direction.

G represents a chain, which is connected to the heel or rear part of the tongue *b*, as is clearly seen in fig. 2, and also to the stationary part *A*, to prevent the pole *B* from swinging around too far, to get the horses into or too close to the sickle.

The end of the double-tree *C* is also connected to said chain *G* by a chain, *H*, which serves to prevent the evener or double-tree from swinging around too far and getting in the way of the reel, and also serves to hold up the chain *G*, to keep it around the heel of the

tongue *b*, as indicated in fig. 2, and prevent its falling below said tongue *b*, which would allow the pole *B* to swing around too far.

If desired, the chain *H* could be connected to a suitable fastening upon the part *A*, instead of being attached to the chain *G*.

From the foregoing description, it will readily be understood that when the machine is being drawn forward by a draught upon the double-tree, the tongue *b* sets back its entire length into the recess *a*, as is indicated in fig. 1.

The side-draught being upon the side upon which the pin *p* is arranged, it is obvious that the pole *B* remains rigid when in this position, as the point of the tongue *b* sets back into the corresponding socket at the rear end of the recess *a*, and thus prevents the rear end of the pole *B* from slipping out of its recess or rest in *A*.

But when the said forward draught ceases, and the horses commence turning around towards the side on which the pin *p* is placed, the force upon the front end of *B* moves it forward, and withdraws the tongue *b* from its socket in *a*, as indicated in fig. 3, so that the pole *B* may swing out upon one side, as clearly shown in fig. 2, the chain *G* preventing a movement too close to the cutter, as aforesaid, and the chain *H* also operating as aforesaid.

As soon, however, as the pole *B* gets in line with the part *A*, and the direct draught is applied to move the machine forward, the pole *B* moves back, the point of the tongue *b*, entering the socket in *a*, when the side-draught gives rigidity to the pole *B*, as desired.

Instead of the chain *G*, any other suitable device may be employed as a stop for the swinging of the pole *B*.

It will be observed that the point and rear end of *b* is faced with metal, to prevent its wearing out, and also that metallic plates are applied upon each side of the tongue *b* where the slot *c* is formed, to keep the said slot from being worn too wide.

It may further be observed, that any other suitable arrangement, which will accomplish the same result, may be used in place of the pin *p* and its supports *d d'*.

Having described the construction and operation of my invention, I will now specify what I claim, and desire to secure by Letters Patent.

1. I claim forming a lateral joint in the draught-pole or tongue *A B*, by means of a pivoted connection, when a slight longitudinal movement is permitted in *B*, substantially in the manner and for the purposes shown and set forth.

2. I claim, in combination with a draught-pole, *A B*, jointed as described, provided with a suitable stop, *p*, the chain *G*, arranged and operating in the manner shown and described.

3. I claim the combination of the double-tree *C* and chain *H* with the jointed draught-pole *A B*, arranged and operating in the manner set forth.

JOSEPH WADLEIGH.
